UNITED STATES PATENT OFFICE.

ARTHUR WHEATLEY, OF PHILADELPHIA, PENNSYLVANIA.

MECHANICAL MOVEMENT.

1,262,889.

Specification of Letters Patent. Patented Apr. 16, 1918.

Application filed March 3, 1917. Serial No. 152,252.

To all whom it may concern:

Be it known that I, ARTHUR WHEATLEY, a citizen of the United States, residing in the city and county of Philadelphia, State 5 of Pennsylvania, have invented a new and useful Mechanical Movement, of which the following is a specification.

My invention consists of a mechanical movement particularly applicable to a washing machine embodying a plurality of beaters, means for operating the same in opposite directions, means for separating the beaters to such an extent that articles to be washed may be placed between the same, and 10 means for connecting the body of a beater with the rim thereof, and removing it from the same, as will be hereinafter set forth.

The invention is satisfactorily illustrated in the accompanying drawing, but the important instrumentalities thereof may be varied, and so it is to be understood that the invention is not limited to the specific details shown and described.

Figure 1 represents a side elevation of a 25 washing machine embodying my invention.

Fig. 2 represents a horizontal section thereof on line 2—2 Fig. 1.

Fig. 3 represents a central vertical section thereof.

Fig. 4 represents a side elevation of one 30 of the standards employed.

Fig. 5 represents a vertical section thereof on line 5—5 Fig. 4.

Fig. 6 represents a top or plan view of a 35 portion of the rim of the upper device employed.

Fig. 7 represents a horizontal section of a portion on line 7—7 Fig. 1.

Fig. 8 represents a horizontal section of 40 a portion on line 8—8 Fig. 4.

Fig. 9 represents a top or plan view of the lower beater employed.

Similar numerals of reference indicate 45 corresponding parts in the figures.

Referring to the drawings.

1 designates the tub of a washing machine to which in the present case the invention is more particularly applicable. To opposite places of said tub are secured the standards 50 2 on whose inner faces are the vertically arranged beads 3 forming on the sides thereof on said standards the passages or ways 4 on which beads and ways are movably guided slides or sliding bars 5.

55 Within the tub are the horizontal devices, such as the beaters 6 and 7, one below the

other, the body of the upper beater 6 being formed of rods or slats 8, whose ends are supported on and secured to the rim 9 as the circumference of said beater 6.

60

The lower beater 7 has its body formed of rods or slats 10, the connecting pins 11 passing through the same at an angle thereto,

and the rim 12 which comprises the rim of 65 said beater 7, it being noticed that the ends of the rods 10 are shouldered and in Fig. 2

rest on the top of the rim 12 and bear upwardly against the under side of said rim, thus connecting said rods with said rim, but in order to assemble said rods and rim the 70

inner periphery of said rim has vertical slots 13 therein so that the adjacent end portions of the rods may be passed through said slots and then when the body of the beater is 75

turned said portions are on the under side of the rim, thus connecting said body with the latter, as clearly shown in Fig. 2. When the body is turned in the opposite direction until said portion registers with the slots the

body may be lifted clear of the rim, so that 80 when the upper beater 6 is raised to its highest position, say above the top of the tub as shown in dotted lines Fig. 1, as will be hereinafter more fully referred to, said body

may be removed from the tub for the purpose of cleansing, repairs, packing, etc.

It will be seen that the slides 5 are of 85 different lengths, the shorter slides having on their lower end the limb 14 which is guided on the beads 3 and guides 4 and secured to the rim 9 of the upper beater.

The longer slides 5 are passed freely 90 through slots in the rim of the upper beater, see Fig. 6, and extended to the lower beater below the upper beater and have on their lower ends the limb 15 which is guided on the beads 3 and ways 4 and secured to the rim 12 of said lower beater. Each slide has

pivotedly connected with it the link 16, the 95 pivots 17 whereof are movable in the vertical slots 18 in the standards 2, thus guiding said slides and consequently the beaters true and steady in their motions.

The upper ends of said links are connected by pivots 19 with the levers 20, said 100 pivots being on opposite sides of the pivot or axis 21 of said levers, said pivot or axis

being fitted in the slots 22 in the upper portions of the standards 5, said levers being connected by the operating handle 23 of the 105

machine, it being noticed that when the levers are operated, the upper beater is low-

110

ered and the lower beater is raised, thus separating the beaters, then the lower beater is raised, and the upper beater is lowered, consequently the articles placed between the beaters are subjected to pounding or beating and squeezing operations, thus washing the same, after which said articles may be removed from the beaters and consequently from the tub, but to accomplish the supplying and removal of the articles the upper beater requires to be raised to an extent above the top of the tub, so that the articles can be introduced thereunder and removed therefrom. For this purpose the slots 22 are elongated upwardly above the axis 21 of the levers 20 to allow said axis to slide upwardly above its normal position and allow the levers 20 to be raised on the standards, and the beads 3 extend for only a part of the length of the standards terminating below the slots 18, and consequently some distance below the tops of the standards at 24 leaving the inner faces of the standards unobstructed above said terminals as shown in Fig. 4, consequently the top beater 6 can be raised to a greater extent than shown in full lines Fig. 1, to the horizontal position shown in dotted lines, in said Fig. 1, and owing to the giving of the pivotal links 16 as toggles, see dotted lines Fig. 1, it may be turned angularly upwardly, as shown in dotted lines at the right side of said Fig. 1, thus raising the upper beater whereby articles to be washed may be placed on the lower beater. In this motion of the beater, the left hand slide may leave the standards just above the top terminals 24 of the bead 4, as shown by the arrows Figs. 6 and 7. Then the upper beater may be restored to its normal place in the tub, the levers 20 lowering in the slots 22, the links 16 resuming their normal positions, and the left hand links reoccupying their ways 4, when the upper beater descends and so again enters the tub, the two beaters then being operative as before.

Having thus described my invention what I claim as new and desire to secure by Letters Patent, is:—

50 1. A standard, slides guided on said standard, independently-movable devices one above the other, one connected with one of said slides and the other with the other

slide, said standard having therein a vertically extending elongated slot, link members pivotally connected with said slides respectively, and a handled oscillatory lever pivotally mounted on said standard and pivotally connected with said link members, the pivot of said lever being vertically movable in said slot above its normal position to admit of the elevation of said lever with its pivot and the upper device, and change in angularity of the latter. 55

2. Separably independently movable devices one above the other, standards having vertically arranged beads on their inner faces, vertically slidable bars movable on and guided by said beads, one of said bars being connected with one of the devices and the other bar connected with the other device; an oscillatory lever pivotally mounted on said standards, and links pivotally connecting said lever upon opposite sides of its pivot with said bars, said standards being 70 provided with vertically extending slots and the pivot of said lever being vertically movable in said slots above its normal position to admit of elevation of one of said devices and a change in angularity. 75

3. Separably movable devices one above the other, standards having vertically arranged beads on their inner faces, vertically slidable bars movable on said beads, one of said bars being connected with one of the 85 devices and the other bar connected with the other device, an oscillatory lever pivotally mounted on said standards, and links pivotally connecting said lever upon opposite sides of its pivot with said bars, said standards being provided with vertically extending slots and the pivot of said lever being vertically movable in said slots above its normal position to admit of elevation of one of said devices and a change of angularity, said beads terminating on said standards intermediate of the top and bottom thereof and below the lower ends of said slots and the pivots connecting said links with said bars being upwardly movable in 90 said slots above their normal position. 95

ARTHUR WHEATLEY.
